[57] **ABSTRACT**

A method is disclosed for the treatment of cardiac bradycardias, i.e., slow, maladjusted heart rhythms and frequencies which often occur in heart block. It comprises intravenously administering therapeutic amounts of scopolamine methylbromide in order to increase the heartbeat frequency without causing certain undesirable side effects.

6 Claims, No Drawings

METHOD OF TREATMENT OF CARDIAC BRADYARRHYTHMIAS

BACKGROUND

In the treatment of vagal-induced bradyarrhythmias as well as other malfunctions of the heart wherein heartbeat frequency slows, it is generally necessary that such frequency be increased. In the past, drugs such as atropine and atropine sulfate have been used for that purpose. While such compounds are usually effective in increasing heartbeat frequency, they often cause serious side effects which detract from their usefulness. A particularly undesirable consequence of the use of these drugs is the possibility that the patient might suffer hallucinations and become agitated or even delirious. It will be appreciated that such central nervous system (CNS) side might be extremely hazardous for a cardiac patient who normally requires complete rest and quiet.

Additionally, it has also been reported that atropine and like substances produce in some patients an initial arrhythmic bradycardia before the normal heartbeat frequency increase effects become apparent; this is also thought to be due to the central nervous system action of such drugs. Other complications that can arise through the administration of these drugs are supraventricular and ventricular ectopic beats or ventricular fibrillation.

SUMMARY

The present invention is directed to overcoming the difficulties inherent in the administration of drugs heretofore used in the treatment of cardiac bradyarrhythmias. The method herein disclosed is as effective as treatment with atropine and allied substances in increasing heartbeat frequency, but it's use is free from the dangerous CNS side effects, especially hallucinatory effects, mentioned above.

Generally speaking, the method comprises the intravenous administration of therapeutic amounts of scopolamine methylbromide or homologs thereof which are in the form of quaternary ammonium compounds under bloodstream conditions. Scopolamine methylbromide is of the formula:

Specific homologs and analogs of scopolamine methylbromide believed to operate in a similar medicinal fashion would include scopolamine ethyl-, propyl- and butyl halides of bromine, chlorine and flourine and the structural isomers thereof.

In cardiac treatments of the type relevant to this invention it is often difficult or impossible to determine beforehand the optimum level of heartbeat frequency that should be reached for a particular patient. Further, it is well-known that a beneficial heartbeat frequency for a given patient under certain conditions may not be at all suitable for another patient of differing condition. Therefore, in general it can only be said that the present invention should be utilized in order to raise the heartbeat frequency to a therapeutic level for a particu-

lar patient. In normal situations, however, this rate has proved to be in the range of from 70 to 110 heartbeats per minute, and the presently disclosed methods operate to raise the frequency to those levels without undesirable CNS complications.

The total dosage required for such action will likewise vary from patient to patient. The age, general size and cardiac condition of the subject may influence this amount, although it is believed the patient's body weight is the most important single factor. On that basis, the total dosage should fall within the range of about 0.75 to 10 micrograms per kilogram of body weight, the preferred dosage being about 5.7 mg/kg.

The invention may be advantageously practiced by a method of sequential administration. It is contemplated in this refinement that the drug (preferably scopolamine methylbromide) be given in a stepwise fashion by administering minor fractional amounts of a total therapeutic dosage, with time intervals between each fraction and with continuous monitoring of the heart signs of the patient. The total dosage administered to the patient is thereby carefully controlled to produce only the desired stimulation of heartbeat frequency.

Scopolamine methylbromide has been utilized for many years as an antispasmodic or anticholinergic in the treatment of peptic ulcers and other gastro-intestinal disorders and for hyper hydrosis and excessive salivation. Other uses have been found for this compound in connection with the treatment of functional diarrhea associated with hyper motile dysfunction of the intestinal tract. For such uses, the drug has usually been administered subcutaneously or intramuscularly at intervals of 6 to 8 hours. As reported in literature [See *The Pharmacological Basis of Therapeutics*, 2d. Edition (1955), p. 559-560, and the U.S. Pat. of Visscher (2,753,288)] the administration of the drug for such purposes has not been found to increase or appreciably affect pulse rate.

DETAILED DESCRIPTION AND PREFERRED EMBODIMENTS

The scopolamine methylbromide to be administered in accordance with the present invention is commercially available in sterile aqueous solution, normally a 1 percent solution although other concentrations may be prepared and used, and is also available as a crystalline solid from which aqueous solutions of desired concentration may be prepared. The drug may be produced by reacting scopolamine hydrobromide trihydrate with methyl bromide according to procedures fully explained in the aforementioned Visscher Patent.

As already explained, in the normal treatment of cardiac patients suffering from bradyarrhythmias it has been found that no single dose regimen is applicable to all patients, and that individual experimentation is usually required. In general, however, it has been found that a total intravenous dosage of from 0.75 to 10.0 micrograms per kilogram of patient body weight, and preferably not exceeding 6.0 micrograms per kilogram of body weight, will serve the therapeutic purposes outlined above.

The importance of carefully regulating dosage levels is apparent from the further discovery that an insufficient dose might produce a short period of increased vagal activity (i.e., the heart rate might slow further) whereas if the dose is too large the heart rate might in-

crease excessively. It is therefore particularly advantageous to sequentially administer the drug in fractional amounts of the total dosage while continually monitoring the heartbeat frequency of the patient. In such a way, the administration can be terminated when the heartbeat reaches the desired frequency, e.g., a level of from 70 to 110 heartbeats per minute.

In further clinical tests, it has been found that the correct dosage level can most effectively be reached by an electrocardiographically monitored sequential administration of scopolamine methyl bromide over a total time period of 10 to 30 minutes according to the following schedule:

a. initially intravenously administering an amount of the drug of from one-eighth to one-fourth of the total dosage;

b. then, after a period of from 2 to 10 minutes, intravenously administering an amount of from one-eighth to one-fourth of the total dosage;

c. then, after a period of from 2 to 10 minutes, intravenously administering from one-eighth to one-fourth of the total dosage;

d. finally, after a period of from 2 to 10 minutes intravenously administering the remaining fraction of the total dosage.

Once the optimum total dosage for a given patient has been determined, a lesser number of steps, or even

The following table shows the effects of scopolamine methylbromide on seventeen patients suffering from cardiac bradyarrhythmias, mostly due to heart block.

In the course of treatment a 1 percent sterile solution of scopolamine methylbromide was intravenously administered in sequential fashion, and the patient's heart signs were continuously monitored by means of an electrocardiograph. As evident from the date, each patient reacted individually to the treatment, some reaching a desirable heartbeat frequency after three injections and others requiring four. Similarly, the total dosage required varied between patients of differing body weight.

In the course of these clinical tests, the patient's heartbeat was initially checked, and a minor fractional amount of an anticipated total dosage was given intravenously. After five minutes this was repeated, and the process continued with five minute periods between doses. The total dose was anticipated to be 5.7 micrograms scopolamine methylbromide per kilogram body weight, and was administered according to the following schedule, with continuous monitoring:

- a. $\frac{1}{8}$ dose initially;
- b. $\frac{1}{8}$ dose 5 minutes later;
- c. $\frac{1}{4}$ dose 5 minutes later; and
- d. $\frac{1}{2}$ dose 5 minutes later.

TABLE

Age of patient	Initial heartbeat, beat/min.	Initial dose, μ g.	Heartbeat frequency, beat/min.	Second dose, μ g.	Heartbeat frequency, beat/min.	Third dose, μ g.	Heartbeat frequency, beat/min.	Fourth dose, μ g.	Final heartbeat frequency, beat/min.	Total dosage, μ g.

a single-step administration of the drug, may be appropriate or desirable for subsequent treatment.

In the following example and accompanying clinical data, it has been found that scopolamine methylbromide, when employed according to the procedures herein, produces the desired effect of increasing heartbeat frequency in patients with cardiac bradyarrhythmias. In no such cases have hallucinations and other undesirable CNS side effects of the type associated with atropine and allied substances been observed or reported. Such favorable results are believed to arise at least in part from the fact that scopolamine methylbromide is a quaternary ammonium compound which does not cross the blood-brain barrier to produce undesirable effects upon the central nervous system.

The following example serves to illustrate further the nature of the present invention and the manner by which it can be practiced.

While in the foregoing I have disclosed the method of the invention in considerable detail for purposes of illustration, it will be understood that many of these details may be varied without departing from the spirit and scope of the invention.

I claim:

1. A method of increasing the frequency of human heartbeat in the treatment of cardiac patients suffering from bradyarrhythmias which comprises intravenously administering to said patients scopolamine methylbromide of the formula:

in a total dosage sufficient to raise the heartbeat frequency to a therapeutic level.

2. The method of claim 1 wherein said dosage is sequentially administered in fractional amounts of said total dosage while continuously monitoring the heartbeat frequency, said administration being terminated when said heartbeat frequency reaches a therapeutic level.

3. The method of claim 1 wherein said therapeutic heartbeat frequency is from 70 to 110 heartbeats per minute.

4. The method of claim 1 wherein said total dosage is from 0.75 to 10.0 micrograms of scopolamine methylbromide per kilogram of patient body weight.

5. The method of claim 4 wherein said total dosage is sequentially administered as needed until the heartbeat frequency reaches a level of from 70 to 110 heartbeats per minute, according to the following schedule, while continuously monitoring said heartbeat frequency:

a. initially administering an amount of from one-eighth to one-fourth of said total dosage;

b. after a period of from 2 to 10 minutes, administer-

ing an amount of from one-eighth to one-fourth of said total dosage;

c. after a period of from 2 to 10 minutes, administering an amount of from one-eighth to one-fourth of said total dosage; and

d. after a period of from 2 to 10 minutes, administering the remaining fraction of said total dosage.

6. The method of claim 1 wherein said total dosage is about 5.7 micrograms scopolamine methylbromide is sequentially administered as needed until the heartbeat frequency reaches a level of from 70 to 110 heartbeats per minute, according to the following schedule, while continuously monitoring said heartbeat frequency:

a. initially administering an amount equal to about one-eighth of said total dosage;

b. after a period of about 5 minutes, administering an amount equal to about one-eighth of said total dosage;

c. after a period of about 5 minutes, administering an amount equal to about one-fourth of said total dosage; and

d. after a period of about 5 minutes, administering the remaining fraction of said total dosage.
